UNITED STATES PATENT OFFICE.

TOM WILSON, OF CHICAGO, ILLINOIS, ASSIGNOR TO WILSON-JACOBS DRUM MANUFACTURING COMPANY, OF CHICAGO, ILLINOIS, A CORPORATION OF ILLINOIS.

DRUM.

1,254,757.

Specification of Letters Patent. Patented Jan. 29, 1918.

Original application filed December 5, 1913, Serial No. 804,896. Divided and this application filed March 23, 1914. Serial No. 826,800.

To all whom it may concern:

Be it known that I, Tom Wilson, a citizen of the United States, residing at Chicago, in the county of Cook and State of Illinois, have invented certain new and useful Improvements in Drums, of which the following is a specification.

This application is a division of my former application Serial No. 804,896, filed December 5, 1913, and the purpose of this invention is to provide improved attachments for adjusting the snares of a snare drum. One object of my invention is to provide means for adjusting a part of the snares independently of the others. Another object is to provide means for simultaneously adjusting all the snares and to provide a quick release for muffling the drum. Other objects will be set forth and made apparent in the following specification, of which the accompanying drawings form a part.

Referring to the drawings—

Figure 1 is an elevation of one form of drum embodying my improvements.

Fig. 2 is a cross section taken on the line 2—2 of Fig. 1 looking in the direction of the arrows.

Fig. 3 is an axial section taken on the line 3—3 of Fig. 2 looking in the direction of the arrows.

Fig. 4 is an enlarged sectional detail view taken on the line 4—4 of Fig. 5 showing a side elevation of the toggle mechanism.

Fig. 5 is an enlarged front elevation of the details shown in Fig. 4, a part thereof being broken away.

Fig. 6 is an enlarged cross sectional detail view taken on the line 6—6 of Fig. 2 showing the means for securing and independently adjusting the snares at one side of the drum.

Fig. 7 is an enlarged detail view of a modified form of the means for independently adjusting the snares at one side of the drum.

Fig. 8 is a side elevation of a modification of the toggle mechanism showing a portion of the drum in section; and

Fig. 9 shows a front elevation of a modified form of the snare-adjusting mechanism shown in Fig. 7.

Referring to the drawings, the drum shell 11 has the two hoops 12 and 13 securing the respective beater head 14 and the snare head

15. A ring 17, which extends around the 55 drum shell and is secured thereto, has equally spaced projections 18 formed thereon, through which are holes or slots parallel with the axis of the drum. Internally screw-threaded sleeves 19, secured to the hoop 12, 60 are engaged by the screws 20 which engage alternate projections on the ring 17. Each screw 20 has a shoulder abutting against its respective projection 18 on the ring 17 and has formed thereon a finger hold 21 by 65 means of which the screws may be rotated to adjust the tension of the beater head 14. The intermediate projections on the ring are engaged by internally threaded sleeves 22 which project toward the snare head side of 70 the drum and are threadedly engaged by studs 23, which coat with lugs 24 fixed on the hoop 13 and which carry finger holds 25 whereby said studs may be rotated to adjust the tension of the snare head 15. These 75 parts are all fully described in my prior application above referred to and are here described generally merely as a basis for showing one adaptation of my improved snare-adjusting mechanism, which will now be described.

The ring 17 is modified at one point around its periphery, as indicated at 26, to provide an attachment for the ends of the snares. At this point there is a channel 27 85 bounded above by the wall 28 in which there is a series of radial slots 29. The inner wall of the channel 27 has little sockets 30, and the outer wall has holes 31, through each of which extends a screw 32 with its end in the 90 corresponding socket 30. Each screw 32 has a milled head 33 to be operated by the fingers, and carries an internally screw-threaded block 34 engaging the same, and from each of said blocks a stud 35 projects through 95 the adjacent slot 29 and has looped around it one bight of the snares 36. The ring 17 is recessed at 37 to permit the snares to pass through it, and the ring 13 on the snare head side of the drum has two opposite holes 38 100 through which the snares pass.

Opposite to the part 26 of the ring 17, the latter carries a channel-shaped clip 39 attached by a screw 40. Within this clip, pivoted at 42, is a channel-shaped link 41 carrying a member 43 at its end on the pivot pin 44. This member 43 carries a sleeve 45, through which passes a stem with a milled

head 48 at one end and a screw-threaded portion 46 at the other end. The collar 47 keeps the stem in the sleeve 45.

The ends of the snares are gripped between the clamping members 49 and 50, which are united by screws 51, the members 49 carrying the screw-threaded sockets 52 to receive such screws. The clamping member 50 has a screw-threaded hole there-through at 53 which is engaged by the screw 46.

By means of the milled heads 33 any pair of snares can have its tension adjusted independently of the others, and since the two snares of a single pair consist of a single catgut, or other strand, looped once around the corresponding stud 35, it will be seen that these two strands of catgut, or the like, will naturally have substantially equal tension. Hence by adjusting the milled heads 33 all the snares can be brought to have the same tension. By adjusting the milled head 48 all the snares will have their tension varied simultaneously alike.

When it is desired to muffle the drum or to produce the tom-tom effect the milled head 48 is simply pushed in a direction radially outward, which breaks the toggle formed by the member 41 and the members 43-45. Whenever it is desired to restore the snares to their normal functional condition, the milled head 48 is pushed in radially and the parts, acting as a toggle joint, put the snares on a tension again. It will be seen therefore that the adjustable connecting means operated by the head 48 constitutes a toggle joint by means of which the snares may be instantly strained or relaxed.

The means for straining the snares may be constructed quite independently of the ring 17, as illustrated in Figs. 7 and 8. In this case the member 26' corresponds to the part 26 shown in Fig. 2, but the member 26' is attached directly to the drum shell 11 by means of two screws 55. The member 26' carries the same mechanism for adjusting the tension of the snares in pairs that has already been described. The toggle joint mechanism can be attached to the hoop 12, as shown in Fig. 8, or it may be attached to the drum shell 11.

Another means for straining the snares constructed independently of the ring 17 is shown in Fig. 9, in which the member 26^a corresponds to the member 26' in Fig. 7, and is attached to the drum shell by screws 56, which engage flanges 57 at the ends of the member. The member 26^a carries substantially the same mechanism for adjusting the tension of the snares in pairs as in the preceding forms, but the flanges 57 are so arranged that the member 26^a lies flat on the drum shell with the slots 29 and screws 32 converging radially downward toward the snare head side of the drum, while in

the preceding forms those members converge radially inward toward the center of the drum. The advantages of this form are that the parts do not project outwardly from the drum surface and that there is less friction on the snares. The studs of screws 35^a may be arranged to carry rollers 58 around which the snares are looped, thus permitting a more ready adjustment of the two snares formed by a single strand relative to each other. In each form of device for attaching the snares to the drum and adjusting them independently of each other, the studs or screws are radially disposed, that is, they converge radially in the general direction of a common center.

It will be seen from the foregoing description that I have provided means whereby the snares of snare drums can be adjusted separately at one end so as to get them all in substantially the same tension, but at the other end they can be strained simultaneously and alike by a single adjustment. Furthermore, at one end they can be instantly strained or released, according as it is desired to have the snare effect or the tom-tom effect.

I have described in detail one embodiment of the means whereby the above results are accomplished, but it is obvious that my invention is not limited to the particular form of parts here described, and I do not wish to be restricted in the scope of my invention, except as defined by the appended claims.

I claim:

1. In a snare drum, a series of screws mounted on one side of the drum, internally screw-threaded blocks on said screws, and snares connected to said blocks, whereby the snares can be separately strained.

2. In a snare drum, an attachment for the ends of the snares on one side of the drum with means for adjusting the snares separately, a clamp engaging all the snares alike on the other side of the drum, and a toggle joint connecting said clamp to the shell of the drum, whereby the snares may instantly be strained alike or relaxed.

3. In a snare drum, an attachment for the ends of the snares on one side of the drum with means for adjusting the snares separately, a clamp engaging all the snares alike on the other side of the drum, and a toggle joint connecting said clamp to the shell of the drum, whereby the snares may instantly be strained alike or relaxed, one member of said toggle joint having screw-threaded engagement with said clamp, whereby the strain of the snares may also be adjusted gradually as desired.

4. In a snare drum, a member attached to one side of the drum having bearings for a series of radially disposed screws, screws in said bearings with milled heads on their

outer ends, internally screw-threaded blocks on said screws, each block carrying a stud, and snares looped on said studs whereby the snares may be strained separately. 30

5. In a snare drum, a shell, a ring around the same, said ring having bearings on one side, radially disposed screws in said bearings, internally screw-threaded blocks on said screws, snares engaging said blocks, and 35
10 toggle mechanism pivoted on the opposite side of said ring and engaging the opposite ends of the snares.

6. In a snare drum, a shell, a ring around the same, said ring having bearings on one side, radially disposed screws in said bearings, internally screw-threaded blocks on said screws, snares engaging said blocks, and toggle mechanism pivoted on the opposite side of said ring and engaging the opposite 40
15 ends of the snares, said toggle mechanism comprising a screw by which the snares may be strained equally and alike.

7. In a snare drum, a member attached to one side of the drum having bearings for a 25 series of radially disposed screws, screws in said bearings with milled heads on their outer ends, internally screw threaded blocks on said screws, each block carrying a stud,

each stud having journaled thereon a roller and snares looped around said rollers, where- 30
by the snares may be strained separately.

8. In a snare drum, a series of screws mounted on one side of the drum, internally screw-threaded blocks on said screws, each block carrying a roller and snares looped 35
around said rollers, whereby the snares can be separately strained.

9. In a snare drum, a channel-shaped clip attached to one side of the drum, a link pivoted on said clip between the opposite 40 flanges thereof, a bearing member pivotally connected to the opposite end of said link and extending outwardly therefrom, a stem rotatably mounted in said bearing member and having an enlarged head, the end of said 45 stem opposite said head being threaded, and a clamping member attached to the snares of said drum and threadedly engaged by said stem.

In testimony whereof, I have subscribed 50
my name.

TOM WILSON.
